UNITED STATES PATENT OFFICE.

CHARLES W. JACKMAN, OF DETROIT, MICHIGAN, AND MILES M. JACKMAN, OF ORLAND, INDIANA.

ROTARY VALVE.

1,402,616.

Specification of Letters Patent.

Patented Jan. 3, 1922.

Application filed April 22, 1918. Serial No. 230,186.

To all whom it may concern:

Be it known that we, CHARLES W. JACKMAN and MILES M. JACKMAN, citizens of the United States, and residents of Detroit, in 5 the county of Wayne and State of Michigan, and Orland, in the county of Steuben and State of Indiana, respectively, have invented certain new and useful Improvements in Rotary Valves, of which the following is 10 a specification.

This invention relates to improvements in rotary valves especially adapted for use on internal combustion engines and it is the principal object of the invention to provide a rotary valve of such construction as will take care of the intaking and exhausting of the fresh and spent gases to and from the combustion chambers of the engine cylinders intermittently and at properly timed 15 recurring periods, thus eliminating the use of separate valves such as now commonly employed to accomplish these ends and as a consequence, requiring the forming of but a single port in the engine cylinders.

Another and equally important object of the invention is to provide a rotary valve, the shell of which is formed with novel exhaust ports which ports are capable of being aligned at properly timed periods with 20 exhaust passages or ways formed in adjacent portions of the engine cylinders whereby to cause the clearing of the cylinders subsequently to the explosion of the gaseous charges.

Other objects will be in part obvious and in part pointed out hereinafter.

The invention consists, furthermore, in the novel arrangements and combinations of the parts of the valve, as well as in the details of the construction of the same, all of which will be more fully described in the following specification and then finally embodied in the clauses of the claims which are appended to this specification and which 45 form an essential part thereof.

In the drawings:

Figure 1 is a fragmentary vertical longitudinal section through the cylinders of an engine showing the arrangement of our improved rotary valve with relation to the heads of the same.

Figure 2 is a vertical section through the cylinder head and the valve taken on the line 2-2 of Figure 1, and

Figure 3 is a similar section taken on line 3-3 of Figure 1.

Figure 4 is a longitudinal sectional view through the rotary valve, showing the spiral dividing wall therein.

Having more particular reference to the drawings, in connection with which like reference characters will designate corresponding parts throughout the several views, C represents the upper portions of the longitudinally arranged cylinders of an internal combustion engine, which as will be understood, are provided with the usual cooling medium circulating jacket, while upon the upper portion thereof there is arranged a transversely disposed head 1, said head being formed to constitute an efficient bearing for the improved valve hereinafter more fully described and having a cap 2 arranged over one end thereof and secured in position by means of bolts 3, which cap is formed with a suitable bearing 4, the purpose of which will be presently apparent. Engaged with the opposite end of the head 1 at a point adjacent the valve receiving opening is an intake manifold 5, which as 75 will be understood has connection with a suitable charge forming device, not shown.

It is to be noted that the casing head 1 is formed with double or spaced walls, thus providing a passage way to permit the circulation of a cooling medium thereabout and about the improved valve; portions of the walls of the head formed with pockets or ways generally indicated by the numeral 6, which ways are interconnected and communicate with an exhaust manifold 7 secured to a portion of the head 1 by bolts or like fastening devices 8. It may be here noted, that these pockets or ways form effectual passages for receiving the spent or exhausted gases from the valve and discharging the same into the exhaust manifold 7.

The improved valve comprises a tubular shell 9 having a plurality of intake ports 10 formed therein in longitudinally stepped relation and a plurality of exhaust ports 11 also formed therein and arranged in longitudinally stepped relation to said shell but aligning with their respective intake ports 10 in the cylinders for an obvious purpose. These ports 10 and 11 are adapted to be intermittently aligned with companion ports indicated by the numeral 12 arranged in the upper portions of the various chambers 105 formed in the casing head 1 and communicating with the chambers of the cylinders C

in order that fresh and spent gases can be conducted to and from the same. Portions of certain of the exhaust ports 11 are enlarged as at 13 and are so positioned as to align with the adjacent pockets or ways 6 intermittently, while others of the exhaust ports 11 have their adjacent extremities connected by an enlarged recessed portion 14, which as will be noted, is so positioned as to intermittently align with the intermediately disposed pocket or way 6.

As means for transmitting rotary motion of the valve, a stub shaft 15 is secured to one end thereof which is closed and is received in the bearing 4 arranged in the cap 2; a sprocket wheel being mounted on its outer end and receiving a sprocket chain 16 or like connection thereabout, which in turn is engaged with the crank shaft on the engine.

Intake and exhaust passage ways are formed in the shell of the valve 1 by arranging a longitudinally extending spiral strip 17 therein, said strip being so disposed as to cause the several ways thereby to communicate respectively with the intake and exhaust ports 10 and 11 which also are properly located; the enlarged portions 14 serving as an outlet for the spent gases discharged into the exhaust way in the valve from the various cylinders of the engine.

In operation, the valve is of course rotated and fresh gas is conveyed by way of the manifold 5 into the intake way formed therein; it being noted in this connection, that the adjacent end of the exhaust passageway is closed by bending the strip downwardly thereover. The gas will be discharged intermittently and at recurring periods into the various cylinders of the engine by way of the intake ports 10 which as hereinbefore stated, are aligned with the

ports 12 in the casing head at properly timed periods, whereupon said ports are disaligned from the ports 12 and the explosion of the various charges in the engine cylinders take place; it being noted that the firing order of the cylinders is *a, b, d, c*. Subsequently to the explosion of the gases in the engine cylinders, the spent gases are exhausted therefrom upon the aligning of the exhaust ports with the ports 12; said spent gases passing into the passage way therefor in the valve and discharging therefrom by way of the enlarged portions 13 and 14 into the pockets or ways 6 from whence they are conveyed by the exhaust manifold 7 outwardly into the atmosphere.

Manifestly, the construction shown is capable of considerable modification and such modification as is within the scope of our claims, we consider within the spirit of our invention.

What we claim is:—

The combination with an engine cylinder head having a plurality of longitudinally disposed ports, portions of the walls of the engine casing being formed with pockets opening into the head, a tubular valve rotatably mounted in the head and having intake and exhaust ports arranged in a step by step manner circumferentially of the valve, certain of the ends of certain of said exhaust ports being enlarged, and the adjacent ends of the remaining exhaust ports being connected, and a partition arranged longitudinally and spirally within the valve to provide independent ways therein communicating with the respective intake and exhaust ports.

In testimony whereof, we affix our signatures hereto.

CHARLES W. JACKMAN,
MILES M. JACKMAN.
